UNITED STATES PATENT OFFICE.

ELMER F. FROST, OF CRYSTAL, MICHIGAN.

GRINDING MACHINE.

Application filed January 8, 1921. Serial No. 435,970.

To all whom it may concern:

Be it known that I, ELMER F. FROST, a citizen of the United States, residing at Crystal, in the county of Montcalm and 5 State of Michigan, have invented certain new and useful Improvements in Grinding Machines, of which the following is a specification.

This invention relates to machines for 10 automatically finishing articles, as by grinding or analogous operations. The invention, while capable of general application, finds advantageous use in grinding machines for finishing the faces of cylindrical articles or 15 rings, such as piston rings, ball races and the like.

The primary object of the invention is to provide in combination, a tool for finishing articles, a continuously movable article carrier or holder for feeding the articles to the tool, and for removing them therefrom, and means for automatically delivering the articles to the continuously moving carrier.

Another object of the invention is to provide in combination with the foregoing, 20 means for finishing the articles on a plurality of faces, without necessitating the removal of the articles from the machine prior to their completion.

Another object of the invention is to provide in a machine for automatically finishing articles, an electromagnetic chuck, a continuously movable carrier or holder for advancing articles across the face of the chuck and 35 into engagement with a finishing tool, and controlling means for the chuck operable by movement of the latter to cause the chuck to grip and later release the articles at proper intervals.

A further object of the invention is to provide a continuously movable article carrier or holder in combination with means automatically delivering articles thereto and also means whereby the articles are caused to be 45 automatically discharged from the carrier on completion.

Still another object of the invention is to provide an article holder or carrier having means for finishing the article co-operating 50 therewith, and means whereby said finishing means may be readily and easily adjusted relative to the article carrier.

Other objects and advantages of the invention will become apparent during the 55 course of the following description.

In the accompanying drawings forming a part of the application wherein like numerals are employed to designate like parts, throughout the several views,

Figure 1 is a plan of the machine.

Figure 2 is a fragmentary side elevation, parts being broken away.

Figure 3 is a fragmentary, vertical section of a part of the invention, and

Figure 4 is a sectional view of the delivering mechanism.

Referring to the drawings wherein for the purpose of illustration is shown the preferred embodiment of the invention, the numeral 5 designates the top or surface plate 70 of the machine frame, upon which revolves an article or work carrier or holder in the present instance being a disk 6. The invention being particularly adapted for grinding faces of piston rings, this disk is provided with a plurality of concentrically arranged circles of openings 7 adjacent the circumference of the disk. These openings are of a size to receive piston rings and to retain them in proper position relative to the 80 disk. A vertical shaft 8 is provided at its upper end with a reduced threaded portion 9 which is extended through and secured to the hub portion 10 of the revolving carrier 6, a nut 11 being threaded upon this reduced 85 end to secure the same in the hub. A worm wheel 13 is keyed to the shaft a distance below the revolving carrier for meshing engagement with a worm 15 carried by an operating horizontally disposed shaft 14 which 90 receives its power from any suitable source.

Worms 15 are also carried by the shaft 14 in spaced relation from the worm 13 for meshing engagement with worm wheels 16 keyed or otherwise secured to chuck shafts 17. 95 These chuck shafts are mounted vertically within the machine and are arranged at approximately the end of a quadrant of the carrier disk 6 and beyond the periphery thereof. The two worms 15 of the operating shaft are right hand while the worm 13 is left hand, so that the chuck shafts are operated counter-clockwise and the carrier shaft is rotated in the reverse direction.

Chucks 18 and 19 are keyed to the shafts 105 17; and although any kind of chuck may be used, I prefer to employ a type having four magnetic coils arranged at equal distances around the chuck as clearly seen in Figure 1.

As the chucks are identical in construction 110

and are only reversed in position as shown in Figure 2, a description of one will suffice in so far as the chuck construction is concerned. A plurality of copper sectors are carried by 5 each of a pair of fiber rings 20, one terminal of each coil 19 being connected to a segment on one ring, while the other terminal is connected to a corresponding segment on the other ring.

10 In order to furnish electricity from any suitable source a pair of contact brushes 21 are secured to and insulated from a bushing 22 surrounding each shaft 17. These brushes each consist of an arcuate shaped plate 15 which extends substantially one fourth the way around a circle and are disposed opposite each other. The chuck 18 has a portion thereof extending beneath the carrier disk 6 so that its upper face engages the under face 15 of the disk beneath the rows of openings 7. The other magnetic chuck 19 is disposed over the carrier 6 so that a portion thereof overlaps the disk sufficiently to cover openings which pass beneath the chuck.

20 Each chuck has a threaded portion 23 on its respective shaft 17 screwed therein. An enlargement 24 is provided upon each shaft 17 and in the case of the chuck 18 is of inverted frusto-conical shape to fit and rest in 30 a similarly shaped end of the bushing 22. This bushing is mounted in a bearing 25 consisting of a pair of vertically spaced plates. The bushing is permitted to move vertically of the plates, constituting the bearings, but 35 is prevented from rotating therein by means of keys 26. The intermediate portion of the bushing is externally screw-threaded as at 27 to co-operate with the threaded openings in a ring gear 28 rotatably mounted between 40 the bearing plate and controlled by a pinion 29 rotatably mounted in one of the plates and operated by a crank 30. As clearly seen in Figure 2, the pinion 29 meshes with the ring gear 28 to cause rotation thereof, and 45 the threads of the ring gear meshing with those of the bushing 22, causes vertical adjustment of the latter, and consequently of the magnetic chuck.

50 The frusto-conical enlargement 24 of a spindle 31 mounted upon the shaft extension 17 is seated within a similarly shaped recess in a bushing 32. This bushing is elongated and provided with a bore 33, and an enlarged portion 34 thereof to receive the 55 extension 35 of the shaft 17 and the shaft spindle 31. This bushing also extends through a bearing slot 36 forming a part of the machine and is prevented from rotation therein by a suitable key 37. The upper end 60 of the shaft extension 35 is screw-threaded and extended above the bearing slot 36 to receive thereon jam-nut 39 for abutment with washers embedded in the spindle whereby the spindle 31 and consequently, the 65 magnetic chuck 19 may be raised and retained.

in said adjusted position when desired. However, in order to permit lowering of the chuck, the bushing 32 is equipped with exterior screw-threads for co-operation with the threaded openings through a ring gear 70 40 mounted in a suitable recess or chamber in the bearing 36. A pinion 41 is suitably mounted in the bearing for meshing engagement with the ring gear, and a crank 42 is provided for imparting rotary movement to 75 the pinion, and consequently the ring gear.

80 A tool, or any other kind of mechanism for operating upon the work is positioned above and beneath the article carrier 6 in opposition to those portions of the magnetic chuck which project within the confines of the carrier. Each tool, in the present instance is of the same construction, so that a description of one will suffice for both. Vertically disposed above the article carrier are a pair of 85 diverging ways 43 having their outer extremities 44 extending toward each other as clearly seen in Figure 1. These ways form a part of an overhanging arm 45 of the machine and mounted therebetween for vertical 90 sliding adjustment are a pair of spaced blocks 46 vertically through which extend a shaft 47 having its lower end secured to a grinding element 48. The end of the shaft 47 adjacent this element is provided with a frusto-conical enlargement 49 which fits within a similarly shaped recess in a packing 49^a secured within the lowermost block 46. A pulley wheel 50 is secured intermediate the ends of the shaft 47 and is 100 disposed between the two blocks 46. This pulley wheel, however, may be replaced by an electric motor if desired. The upper end of this shaft extends through an exteriorly cupshaped member 51 threaded into a recess in the upper block 46, and the extremity of the shaft is reduced and screw-threaded to receive thereon within the members 51 a collar 52 and a nut 53. A ball-bearing sleeve 54 is positioned in the bottom of the cup-shaped member 51 and the bearings are engaged with the collar 53 so as to provide for end thrust of the grinding element or tool in 110 grinding so that it may support the bulk of the weight of the grinding tool when the same is in operation. A screw-cap 55 is threaded into the cupshaped member 51 to close the open end thereof, and to protect the parts within the member 51 against displacement, dust, dirt and the like.

115 In order that the grinding element 48 may be adjusted vertically at will, a screw 56 extends vertically through the blocks 46 and has its lower end equipped with a pinion 57. This lower end of the screw is arranged 120 within a recess in the lower block 46 and is journaled in a suitable supporting bar 58 forming a part of the frame. A pinion 58 carried by a shaft extends into the recess, 125 meshes with the pinion 57 for rotating the 130

screw 56, and a crank is provided upon the shaft for normal control thereof. Obviously, turning of the screw raises or lowers the blocks 46 and also the grinding element 48 to adjust the latter relative to the work.

The means for automatically delivering or feeding the article to the carrier consists of a platform or arm overhanging the article carrier in advance of the grinding tool arranged above the magnetic chuck 18. The platform is provided with a pair of spaced openings or apertures 62 which are adapted for alignment with any of the openings in the two rows of the article carrier. Each opening is surrounded by a plurality of upstanding pins or posts 63 which hold the article or piston rings 64 in stacked formation upon the platform. As best seen in Figure 4, the platform is spaced slightly above the revolving carrier and the lowermost rings 64 in the two openings 62 drop into the first empty openings in the carrier which pass under the platform. Immediately, the next lowest rings in the stack are disposed in position to be delivered upon the revolving carrier.

In order that the articles may be automatically discharged from the continuously rotating carrier 6 when the articles are finished, the surface plate 5 of the machine is provided with a cut-out portion 65, which extends under the carrier so that the rings as they pass the chuck 19 will drop by gravity through the cut-out portion into the receptacle 66.

In operation, the grinding tools 48 are rotated, as well as the operating shaft 14. The latter through the worms transmit rotary movement to the electromagnetic chucks 18 and 19, as well as to the continuously revolving carrier 6. It may be here stated that the worm 13 bears ratio to those 15 as the diameter of the article carrier 6 bears to the diameter of either chuck. As stated before, the article carrier will be rotated in a clock-wise manner as well as the grinding tools 48. However, the two chucks rotate in a counter-clockwise manner.

The piston rings in the two openings in the delivery mechanism drop into the openings 7 in the continuously revolving carrier and are supported in said openings by the surface plate 5. The rings are then advanced onto the electromagnetic chuck 18 and beneath the grinding tool 48 thereabove. The machine being properly timed, as the carrier advances the rings upon the magnetic chuck, the brushes 21 will be engaged with the rings 20, thereby closing an electrical circuit and causing energization of the magnetic coil which is just beginning to enter under the carrier 6. The articles in the openings of the carrier will of course be drawn down upon the upper surface of the magnetic chuck and will be

held in proper position so that relative smooth surfaces may be ground upon the upper faces of the piston rings passing under the grinding tool 48. It is to be understood that one of the brushes 21 of each magnetic chuck is disposed under or above, as the case may be, its adjacent grinding tool, and consequently after the rings have been acted upon by the grinding element 48 above the carrier, the magnetic coil of the chuck 18 which has acted upon these rings around, becomes deenergized by the brushes disengaging the rings of the chucks. After these rings have been operated upon by the upper grinding tool, continued rotation of the carrier causes them to pass beneath the portion of the other magnetic chuck 19 which overlaps the article carrier, at which time the brushes of the chuck, contact with the rings to cause certain of the magnetic coils to become energized whereby the two upper surfaces of the rings passing under the chuck will be drawn into engagement therewith while the relative lower grinding tool 48 is acting upon the relative lower surfaces of the rings. The magnetic coil of the chuck 19 which has acted upon the rings becomes de-energized in a manner identical with the chuck 18, so that the rings may be carried around by the carrier to the cut-away portion 65 of the surface plate 5, where they are permitted to disengage from their respective openings and drop by gravity into a suitable collecting receptacle 66. It is to be particularly noted that the article carrier 6 continually revolves to advance the articles from the delivery mechanism to a finishing element, and after they have been operated upon, are removed from said finishing element and advanced by the carrier to the other grinding tool and magnetic chuck.

The foregoing description and accompanying drawings have reference to what might be considered to be the approved or preferred form of my invention. I desire it to be understood, however, that I may make such changes in the construction, combination and arrangement of parts, materials, dimensions, et cetera, as may prove expedient and fall within the scope of the appended claims.

Having thus described my invention, what I claim as new and desire to secure by Letters Patent is:—

1. A machine for automatically finishing articles, comprising in combination, a revolving carrier, magnetic means positioned adjacent opposite faces thereof, and a tool adjacent each magnetic means for finishing articles upon a plurality of faces.

2. A machine for automatically finishing articles, comprising in combination, a revolving carrier having a plurality of article receiving pockets, magnetic means po-

sitioned adjacent opposite faces thereof, and a tool opposing each magnetic means for finishing articles on a plurality of faces.

3. A machine for automatically finishing articles, comprising in combination, a revolving carrier, rotatable magnetic chucks adjacent opposite faces of the carrier, and spaced apart; a tool for each chuck disposed over faces of the carrier opposite the faces adjacent the chucks, and means for automatically energizing and de-energizing said chucks at intervals to hold and to release the articles.

4. A machine for automatically finishing articles comprising, a rotatable carrier, a

pair of tools for finishing articles, one of said tools mounted below the rotatable carrier and in close proximity thereto, and the second tool mounted above the rotatable carrier and in close proximity thereto, a 20 pair of rotatable magnetic chucks, one each adjacent a tool and means for energizing and de-energizing said chucks at intervals to hold and to release the articles.

In testimony whereof I affix my signature in presence of two witnesses.

ELMER F. FROST.
